UNITED STATES PATENT OFFICE.

CLYDE CORNELIUS, OF PITTSBURGH, PENNSYLVANIA.

GAS PRESSURE REGULATING AND MIXING VALVE.

1,229,038.

Specification of Letters Patent.

Patented June 5, 1917.

Application filed April 7, 1916. Serial No. 89,633.

To all whom it may concern:

Be it known that I, CLYDE CORNELIUS, a citizen of the United States, residing at Pittsburgh, in the county of Allegheny and 5 State of Pennsylvania, have invented certain new and useful Improvements in Gas Pressure Regulating and Mixing Valves, of which the following is a specification, reference being had therein to the accompanying 10 drawing.

My invention relates to improvements in gas pressure regulating and mixing valves, the primary object of which is to so construct such a device that it may be used 15 either for natural or artificial gas, and is especially adapted for use where either of said gases vary in pressure.

Another object of the present improvement is to construct such a device that both 20 the gas and air discharging orifices are adjustable and in which each orifice may be set or adjusted independent of the other.

A further object of this invention is to devise a valve for the gas which does not 25 break up the main pressure, but causes it to cushion in the interior of the valve and be discharged at any desired pressure or at full main pressure.

A still further object of the present invention is to so construct the device that it is of 30 simple construction, easy to operate, durable, and can be manufactured to sell at a small price.

Other objects and advantages of the invention will be set forth in detail in the accompanying description and drawings, in which—

Figure 1 is a perspective view of my improved gas valve and mixer in operation.

Fig. 2 is a vertical sectional view of the valve and mixer.

Fig. 3 is a horizontal sectional view through the core of the valve showing the plurality of orifices therein.

Fig. 4 is a fragmentary disassembled perspective view of the end of the core and the means for holding it within the casing.

Fig. 5 is a fragmental vertical sectional view, taken on the line 5—5 of Fig. 2, and 50 looking in the direction of the arrow.

Referring now to the drawings in detail in which like reference numerals designate similar parts, 1 represents the body portion or casing of the valve having a tapered 55 opening 2 through its center to receive a

revoluble tapered core 3. The casing 1 is provided with projections 4 and 5 at right angles to the core 3, provided with passages 6 and 7 adapted to be thrown into communication with each other by the core 3, as will be hereinafter set forth. The projection 4 is provided with internal screw threads 8 to receive the threaded end of a pipe 9, communicating with the gas main (not shown). The other projection 5 is provided with external screw threads 10, upon which is threaded the air mixing attachment, herein-after to be described.

In pressure regulating and mixing valves heretofore used for the feeding of gas to furnaces and gas ranges, there has been considerable difficulty experienced where the valve was constructed with tortuous passages and a multiplicity of movable parts. By my improvement I intend to introduce a full amount of pressure into the valve casing and there pocket it when the valve is closed. With this object in view, the core 3 is provided at its center with a chamber 11. One side of the core is provided with three openings 12, 13 and 14, the opening 13 being arranged opposite the center of the core; the openings 12 and 14 being spaced equidistant from the opening 13. Each of these openings at all times communicate with the interior chamber 11 and are adapted to be thrown successively into communication with the pipe 9, through the extension 4 of the valve casing. Directly opposite the openings 12, 13 and 14 are three openings 15, 16 and 17. The opening 16 is arranged directly opposite the center of the core, while the openings 15 and 17 are arranged on each side and equi-distant the opening 16. The openings 15, 16 and 17 are of graduated sizes, the opening 15 being the smallest and the opening 17 the largest. The openings 12, 13, 16 and 17 are arranged in the same plane, while the openings 14 and 15 are arranged in a plane below the plane occupied by the other openings. It is to be understood, of course, that the openings 12, 13 and 14 may all be arranged in stepped position, or in any position on one side of the core, but must, of course, be so spaced that they can be brought into communication with the pipe 9. The openings 15, 16 and 17 may also be arranged in any position so that they may be brought into communication with the extension 7 and also register 110

with their respective openings on the opposite side of the core. The openings 15, 16 and 17 are at all times in communication with the chamber 11 and are adapted to be thrown successively into communication with the extension 5 of the valve casing and thereby convey gas through the air-mixing device and to the burners, as will be herein-after set forth. The end of the extension 5 adjacent the core 3 is provided with a web 37 provided with a slotted opening 38 as is clearly shown in Fig. 5. The end of the extension 4 adjacent the core 3 is likewise provided with a web 39 and slotted opening similar to the opening 38. The slotted openings are only of sufficient width to permit one opening on each side of the core to communicate with the passages 6 and 7. Since the openings through the core 3 are arranged in pairs only one pair of openings at a time can pass gas through the core 11 and passages 6 and 7.

By referring to Fig. 3, it is clearly seen that the openings 12 and 17 will register at the same time; 14 and 15 registering at the same time and 13 and 16 registering simultaneously, the registering openings serving at different times to throw the pipe into communication with the air mixing device.

The core 3 is revolved by means of a handle 18 having a squared opening 19, fitting on the squared end 20 of the core 3. The lower end of the core where it projects beyond the end of the casing 2, is formed with a shoulder 21 having a squared portion 22 and a screw-threaded extension 23. A washer 24, having a squared portion 25 to fit the squared portion 22 is fitted on the shoulder 21 and fastened by means of a nut 26. In this way the turning movement of the core occurs between the end of the casing 1 and the washer 24. The handle 18 is provided with an extension 27 on one side which forms a pointer to indicate when the various openings in the core are passing gas through the valve. In order to accomplish this purpose, markers 28 are provided on a plate 29 cast on the upper end of the valve casing 1. Stops 30 and 31 are also provided at the ends of the plate 29 to limit the movement of the handle. When the handle is in the position shown in Fig. 1, none of the openings register with the pipe 9 and consequently the valve is closed and no gas is flowing therethrough. When the marker 27 is opposite the first mark on the plate 29, the openings 14 and 15 are thrown into communication with the pipe 9 and the extension 5 respectively; when opposite the second mark on the plate 29, the openings 13 and 16 are in communication and when the marker 27 reaches the stop 31, the openings 12 and 17 are thrown in communication. It is to be understood that due to the central chamber 11 in the core 3, sufficient gas is

pocketed therein so that as the handle 18 is turned to register, first one orifice and then the other, the flame at the burner will not be extinguished, but will burn at all times as the handle 18 is moved over the different orifices. 70

The air mixing device which is used in co-operation with my improved valve, heretofore described, comprises a body-portion consisting of a pipe 32 having one end outwardly flared forming a conical-shaped portion 33 across the outer face of which is formed a web consisting of arms 34, which carry at their ends a collar 35 internally screw-threaded meshing with external screw threads 10 on the extension 5. A pipe 36 fits within the pipe portion 32 and this pipe 36 conveys the mixed gas and air to the burners of either a furnace or burners of a gas range. The body portion of the air mixing device may be adjusted in or out by virtue of the collar 35 screwing in and out on the screw threads formed on the extension 5. When the collar 35 is screwed in toward the valve casing as far as the screw-threads permit, the passage of air into the conical portion 33, will be small for the reason that the space between the extension 7 and the inner face of the flared portion 33 is slight, as is shown in Fig. 2. However, when the collar 95 35 is screwed outwardly as far as the screw-threads permit a large space will be left between the inner end of the extension 5 and the inner face of the conical-shaped portion 33. In this way the air fed into the pipe 36 100 may be varied by varying the distance between the inner end of the extension 5 and the adjacent face of the conical portion 33. The body-portion of the mixing device is held at any adjusted position by means of 105 set screw 37 which impinges against the pipe 36.

It is well known to those skilled in this art that great difficulty is experienced when operating furnaces and stoves, due to the 110 fact that the pressure in the mains often-times changes and the gas and air fed to the burners consequently varies. Where valves are used having a constant intake and outlet the amount of air or gas cannot be so mixed 115 as to compensate for the difference in pressure. This is specially true where it has been attempted to use the same character of valve for burning both artificial or natural gas, since it requires different mixtures of air 120 for perfect combustion. In order to accomplish this the present invention is so constructed that it can operate with either natural or artificial gas, or can properly mix the gas and air whether the pressure be 125 low or high. For instance, should the pressure in the main pipe be high, the core of my valve would be turned so that the openings 14 and 15 are thrown into communication with the pipe 9 to feed the gas from the 130

said pipe through the air mixing device and into the pipe 36. After the valve has been turned to the right position, the conical portion 33 of the air mixer may then be moved 5 in or out until the flame at the burner reaches the desired heat or perfect combustion. When the combustion is perfect the conical portion 33 is locked by means of the set screw and the apparatus need not again 10 be touched until the pressure varies. Should the pressure become less, the same operation would then take place and the core would be turned until the next largest opening 16 should be thrown into communication with 15 the gas main. Should the pressure be very low, the largest opening 17 would be thrown into communication with the gas main and the full pressure allowed to pass through the valve with little cushioning effect. It is particularly pointed out that the openings 20 which pass the gas from the main into the inner chamber 11 where it is pocketed are constant, while the openings which discharge the gas from the inner chamber into the air mixing device are of various sizes and the 25 adjustment of the gas is accomplished at this point.

When the device is to be used with natural gas due to the plurality of different sized 30 gas discharge openings and the adjustability of the air supply the best combustion may be accomplished and the device set in its adjusted position. In this way the same device may be used either for natural gas or 35 artificial gas. It is also noted that either the gas regulating portion of the valve or the air regulating portion may be moved independent of the other and set in any position. Due to this construction the gas supply may 40 be set at one place and the best combustion obtained through varying the air which would not be possible were both moving together and would be more difficult should

they both move together though adjustable one independent of the other. 45

It is also to be understood that this mixing valve may be used with any gas burning device where a blue flame is desired, and is readily applicable to gas ranges, heaters and gas burning stoves of any construction. 50

Having thus described my invention, what I claim and desire to secure by Letters Patent is—

1. A gas and air mixing valve comprising a body portion, a revoluble core mounted 55 therein, a gas outlet passage and a gas inlet passage adapted to be thrown into and out of communication by the core, the said core having a plurality of openings of different sizes therethrough, said openings arranged 60 in pairs on opposite sides of the core, the body portion provided with restricted openings adjacent the core, whereby only one pair at a time can register with the inlet and outlet passages in the body portion. 65

2. A gas and air mixing valve comprising a body portion, a revoluble core mounted therein, a gas outlet passage, and an inlet passage adapted to be thrown into and out of communication by the core, the said core 70 having a plurality of openings of the same size on one side thereof and a plurality of openings of different sizes on the other side thereof, said openings also arranged in pairs, each pair comprising a uniform size opening 75 and a variated size opening, the body portion provided with restricted openings adjacent the core, whereby only one pair at a time can register with the inlet and outlet passages in the body portion. 80

In testimony whereof I hereunto affix my signature in the presence of two witnesses.

CLYDE CORNELIUS.
